WILLIAM LINDSAY, OF CHICAGO, ILLINOIS, ASSIGNOR, BY MESNE ASSIGNMENTS, TO ECONOMY FUSE AND MANUFACTURING CO., OF CHICAGO, ILLINOIS, A CORPORATION OF NEW YORK.

ELECTRIC SWITCH.

Application filed July 11, 1923. Serial No. 650,813.

This invention relates to that class of electric switches in which a movable contact member or electrically conductive switch member is operated by actuating means comprising a spring or resilient element and means for setting or flexing and releasing the resilient element to cause the latter to operate the movable contact, to open and close an electric circuit.

10 The principal object of the invention is to provide a simple, economical and efficient electric switch.

Other and further objects of the invention will appear from the following description and claims, and from an inspection of the accompanying drawings which are made a part hereof.

The invention consists in the features, combinations, details of construction, and arrangements of parts herein described and claimed.

In the accompanying drawings, Figure 1 is a view in elevation of an improved electric switch constructed in accordance with my invention, showing the same mounted in operative position in and adapted for use in connection with an electric lamp socket or other device for connecting electric wires or conductors and for making and breaking an electric circuit for lighting or other purposes;

Fig. 2 is a view in transverse section taken on line 2—2 of Fig. 1, looking in the direction indicated by the arrows;

Fig. 3, is an enlarged perspective view of my improved electric switch of the form shown in Figs. 1 and 2;

Fig. 4 is a similar perspective view of an electric switch constructed in accordance with my invention, showing the same provided with a pull chain and reciprocating ratchet mechanism for rotating the actuating spring and its rotative supporting shaft, for setting the spring at a tension in a plurality of predetermined positions successively, to open and close an electric circuit for lighting or other purposes;

Fig. 5 is a transverse sectional view taken on line 5—5 of Fig. 1 looking in the direction indicated by the arrows, and shows the central contact terminal and electric connections forming a part of an electric circuit

within which the contact terminals and other electrically conductive elements shown in Figs. 1 and 2 are embraced; and

55

Fig. 6 is a perspective view of a portion of a modified form of my improved electric switch, showing a modified form of movable contact member or bridging switch member.

In constructing an improved electric switch in accordance with my invention and improvements, I provide a frame 1 which may be of any desired ordinary and well known form adapted to support the operating parts of the device in operative position.

60

In the form of frame shown in the accompanying drawings, however, the frame 1 is formed of a plate or piece of sheet metal cut and bent or stamped to form a base 2 and supporting standards 3 and 4, all

65

formed, by preference, of one integral piece of sheet metal and adapted to be connected with suitably insulated parts of a lamp socket, or other socket, or similar or equivalent device for connecting electric conductors, or for opening and closing an electric circuit for lighting or other purposes.

75

In the form of the device shown in the accompanying drawings a guiding member or guiding stop 5, adapted to support and guide a movable contact member or bridging switch member 6, is provided, and, by preference, also formed in one integral piece with said base 2 and standards or supports 3 and 4.

80

The base 2, standards 3 and 4, and guiding stop 5 thus form a simple and efficient one-piece supporting means or frame for supporting the movable parts of my improved switch mechanism.

85

The standards 3 and 4, which are perpendicular to the face of the base plate 2 and in parallel relation to each other—and also parallel to the guiding stop member 5—are perforated or provided with aligned or registering openings 7 and 8 in which is rotatively mounted an operating member or shaft 9, which is adapted to be turned or rotated intermittently or in a step by step manner in one direction if desired, as in a pull switch, such for example as the pull switch shown in Fig. 4, or turned or partially rotated in either direction or in opposite directions alternately or successively in

90

100 pull switch, such for example as the pull switch shown in Fig. 4, or turned or partially rotated in either direction or in opposite directions alternately or successively in

predetermined order, or as desired, as when used in a snap switch, such for example as the switch shown in Figs. 1, 2 and 3.

In the form of the device shown in Figs. 5 1, 2, and 3 stationary contact terminals 10 and 11 are provided and mounted in an insulating member 12, which may be one of a pair of insulating members 12 and 13 of an electric socket 14, which may be an incandescent electric lamp socket or other form of socket or device for connecting electric conductors of an electric circuit for lighting or other purposes. The insulating socket members 12 and 13 may be formed of porcelain, hard rubber, commercial insulating fiber, insulating composition, or other ordinary and well known or suitable form of insulating material, and are mounted in fixed relation to each other in the usual metallic shell or casing 15, which may be a connecting switch socket or an ordinary incandescent lamp socket, or other similar or equivalent device for connecting or supporting electric conductors of a circuit in or in connection with which my improved switch is to be used.

The base plate 2 of the frame 1 is mounted on the inside of the shell 15, which may be of any desired ordinary and well known form of switch socket casing or shell, and has a cylindrical casing portion 16 which surrounds the insulating members 12 and 13, which are secured in fixed relation to each other on the inside of the shell 15 or socket 14. The insulating plates or members 12 and 13 are so formed as to provide a space 17 in which the frame 1, and the moving parts of the switch supported by said frame are mounted. And the frame 1 is secured to one of the insulating members 12 or 13—for example, the insulating plate 12,—by means of a screw 18' or other suitable securing means which may be of any desired suitable form. And the shell or casing member 16 has an opening 18 which may be of any suitable form adapted to receive or admit an operating element such as the stem 19 of a thumb nut or button 20, or the chain 21 of a chain and ratchet mechanism for operating the rotative switch member or shaft 9, and which chain and ratchet mechanism may be of any desired ordinary and well known or suitable form, and may be operatively connected with the rotative switch member or shaft 9, or other or equivalent means for setting the actuating spring 22 at a tension. In the form of the device shown in Fig. 4 the pull chain or flexible operating member 21 is operatively connected with the rotative shaft or stem 9 by means of a pawl and ratchet mechanism 23 which may be of the usual or any desired ordinary and well known or suitable form of pawl and ratchet mechanism adapted to reciprocate or oscillate back and forth upon

the stem or rotative shaft 9, so as to rotate the latter intermittently or in a step by step manner a half of a complete revolution of said shaft 9 for each forward step or half revolution of the ratchet mechanism 23. 70 The ratchet mechanism 23 is provided with the usual spring—not shown—for retracting or reversing the direction of rotation of the ratchet wheel, and with the usual pawl, click or detent—not shown—operatively connecting the ratchet wheel 24 with the stem or shaft 9 or equivalent element for setting or rotating the actuating spring 22 intermittently. As such pawl and ratchet mechanisms are well known in the art to which this invention relates, it is deemed unnecessary to further describe or illustrate such a device herein.

In the form of the device shown in Fig. 4 stationary contact terminals 25, 26 are shown which are so mounted in the insulation 12 on opposite sides of the stationary guiding and stop member 5 and movable contact member or bridging switch member 6 that the latter engages and forms an electrical connection between said contacts 25 and 26 when the movable contact member 6 is in its lowered position, or at the extremity of its path of movement nearest to the base plate 2. In all other respects the stationary contact terminals 25 and 26 are identical in construction and mode of operation, and electrically connected with the binding posts and other connections and electric conductors in the same manner, as the stationary contact terminals 10, 11 shown in Figs. 1, 2 and 3.

In the form of the device shown in Figs. 1, 2 and 3 the stationary contact terminals 10, 11, are mounted in the insulating member 12 on opposite sides of the movable contact member or bridging switch member 6 in position to engage the opposite extremities or contact surfaces of projecting end portions 27, 28 of the said movable contact member or bridging switch member 6 when the latter is in raised position or at the upper extremity of its path of movement, or, in other words, at the extremity of the movement of the part 6 which is farthest from the base 2. And it is obvious that the stationary contacts 10, 11 may be used with a pull switch, such for example as the switch shown in Fig. 4, as well as with the form of switch shown in Figs. 1, 2, and 3; and the contact terminals 10, 11, 25, 26 may be used with the form of switch shown in Figs. 1, 2 and 3, or Fig. 6, as well as in the form of switch shown in Fig. 4.

In the form of the device shown in Figs. 1, 2, and 3, and also in the form or modification shown in Fig. 6, the guiding member or guiding stop 5 is provided with parallel side margins or guiding edges 29, 30 upon and in sliding engagement with which the

movable contact or bridging member 6 is slidably mounted in position to move into and out of engagement with the corresponding adjacent stationary contact terminals 10, 11, or 25, 26 as the case may be; and a suitable checking device or means for stopping, and restraining, checking and releasing and permitting the free unobstructed snapping movement of the movable contact or bridging member 6 into and out of contact with the adjacent or corresponding stationary contact terminals, is provided: For example, opposed detent openings, notches or sockets 31, 32, are provided, having, by preference, approximately circular walls 33, 34, and each having a side opening or mouth provided with a detent shoulder 36 on one or both sides of such mouth or side opening adapted to slidably and releasably engage and admit, check, or restrain and release and permit the movement of the actuating resilient element or actuating spring 22, the outer or free end 37 of which extends loosely through and is rotative in a circular opening or perforation 38 in the movable contact member or reciprocating bridging switch member 6. An elongated opening or space which may be in the form of an elongated slot 39 is provided between the opposed or upper and lower openings, notches or sockets 31, 32, and is adapted to permit the free reciprocatory movement of the spring 22 through said space or opening or slot 39 from one to the other of said opposed sockets or opposed shouldered openings 31, 32, when the spring is turned to a position in either of said openings 31, 32, to cause it to be first restrained and then released by a corresponding detent or shoulder 36 and allowed to snap past such detent or shoulder and into the opposite socket or shouldered opening or notch 31, 32, carrying with it the movable contact member 6, which is thus actuated by the spring 22 with a quick snapping movement into and out of circuit making and circuit breaking positions, respectively.

The actuating spring or resilient actuating member 22 is rotatively mounted upon a suitable support: For example, said spring is folded upon itself so as to form one or more helical windings or laps 40 which encircle a bent end portion 41 of the rotative shaft or stem 9 already described; and the adjacent or attached end or non-reciprocating extremity 42 of said spring 22 is in engagement with or attached to the stem or shaft 9 in any suitable ordinary and well known manner, for example, by being held or secured in engagement with the shoulder portion 43, or other suitably formed portion of the rotative shaft or stem 9.

The spring 22 thus fixed to the shaft or stem 9 is rotative with the shaft and has an axis of rotation which corresponds with the

axis of the stem or shaft; and the free end and arm portion 37 of the spring 22 thus extends normally from the axis or axial center of the spring outward at an oblique angle with respect to said axis of the spring and of the shaft or stem 9, and is adapted to move back and forth or reciprocate transversely with respect to said axis of rotation and from one side to the other of said axis alternately or successively in predetermined order.

The actuating spring 22 is thus rotative bodily upon its axis, and its projecting arm 37 which normally projects outward radially from and at an oblique angle with respect to the axis of rotation of the spring is adapted to reciprocate or snap from one side to another of the axis of rotation as the spring is turned or intermittently rotated and set at a tension and released, and thus carries with it and propels or drives the movable contact member or bridging switch member 6 into and out of circuit closing position, and into and out of contact with the stationary contact terminals located on opposite sides of said movable contact member 6.

The inner extremity or attached end portion of the spring arm 22 as well as the coiled portion of the spring may be at the axis or center of rotation of the spring, so that when the spring is in normal or released position it extends outward from the axis and at an oblique angle with respect to said axis, on one side of the same, and extends into a corresponding shouldered socket or opening 31 or 32, as the case may be—for example, as shown in full lines in Figs. 1, 3, 4 and 6, respectively.

When the spring 22 is in the position shown in Figs. 1, 3 and 4, in full lines, having carried with it the movable contact member 6, the spring is relaxed, and will so remain until it is turned or rotated a part of a revolution upon its axis which is in a plane perpendicular to the direction of the path of movement of the movable contact member 6 and midway between the opposite extremities of the path of movement of the reciprocating spring arm 37 and of the reciprocating or movable contact member or bridging switch member 6. When the spring arm 37 is thus in released or normal position in either of the sockets or openings 31, 32, it is only necessary to turn the actuating spring 22 half of a complete revolution upon its axis thus turning or partially rotating the spring arm 37 in the socket 31 or 32, as the case may be, to set or position the spring at a tension in such socket or opening 31 or 32, and cause it to be first restrained or releasably held at a tension in engagement with a corresponding detent or checking shoulder 36 which is thus in contact with and in position to first check and then release and permit the free unobstructed movement of the spring. And the spring, thus set or posi-

tioned and releasably held at a tension and then released, is caused to move with a quick snapping action from one socket 31, or 32, and its corresponding detent 36 to another or 5 opposite detent socket or opening, and carries with it with the same quick snapping action, the movable contact member 6, which is thus carried into and out of contact with the adjacent stationary contact terminal or 10 terminals 10, 11, 25, 26, with a like quick snapping movement, so as to open and close an electric circuit in which such stationary contact terminals are embraced, with a quick snapping action. The forming of an arc is 15 thus minimized. And it is evident that the spring 22 may be made as strong, and as quick-acting as desired, and may nevertheless be turned upon its axis and thus set at a tension, and releasably held or restrained by 20 the walls of the socket 31 or 32 as the case may be, while being turned to a position in which it will be first releasably held or checked by a corresponding spring engaging detent 36, and then released and permitted 25 to spring from one socket 31 or 32 into another, and from one side to another of its axis, carrying with it the movable contact member or bridging switch member 6.

From the foregoing description it will be 30 readily understood that the actuating spring 22 may be rotatively mounted in any suitable manner, and is adapted to be turned or rotated intermittently in either direction, or in opposite directions alternately, and that the 35 detents or detent shoulders 36 being located on opposite sides of and at equal distances from the axis of rotation of the spring and between the opposite extremities of the path of movement of the spring, are adapted to 40 check and releasably hold and release the spring in a plurality of predetermined positions on opposite sides of the axis of rotation of the spring, and on opposite sides of the center of the path of reciprocatory 45 movement of the movable contact member and reciprocating spring arm. And the spring and movable contact member are thus releasably held while the spring is at a tension in a plurality of positions alternately 50 or successively in predetermined order and independently of the movable contact member 6. That is to say, the detents 36 are adapted to and in practice do actually engage the spring and hold it releasably at a 55 tension independently of the movable contact member which is thus not subjected to any unnecessary friction and is not required to act as a means for checking its own movement or the movement of the actuating 60 spring, or to serve in any way or in any capacity other than as a means for making and breaking the electric circuit by engaging and disengaging or connecting and disconnecting the contact terminals of the switching 65 mechanism.

In any form of the device in which the actuating spring or equivalent actuating element is only required to be turned or rotated in one direction—as for example, in the case of a pull switch such as is shown 70 in Fig. 3, it is only necessary to have one shoulder or detent 36 for each socket or shouldered opening 31, 32, each of said detents being on the side of the opening or socket which is engaged by the spring as it is set at a tension and released and permitted to escape from such opening and from engagement with such detent. And it is obvious 75 that the intermediate opening, space or slot 39 may be of any desired form and may be of greater width than the space between the detent shoulders 36 of the respective 80 sockets 31, 32, respectively.

The stationary contact terminal or terminals—for example terminals 10, 11, 25, 85 and 26 respectively, or either of said terminals, or their equivalents—are connected with a source of electric supply, and embraced within an electric circuit including a lamp or lamps or other current consuming 90 device to be supplied with electricity, in any desired ordinary and well known or suitable manner. For example, one of the lead-in wires or line wires 44 is connected with the binding post 45 by means of 95 a binding screw 46, or other ordinary connecting means, in the usual manner. The binding post 45 is electrically connected with the stationary contact terminal 11, which is adapted to be in turn connected with and disconnected from the terminal 10, by the movable contact member or bridging member 6, in the manner already described. The connection between the binding post 45 and stationary contact 11 may be in the form 100 of a headed screw 47 adapted to secure said parts in engagement with each other. (See Figs. 2 and 5.) The stationary contact terminal 10 is connected with a center contact 48 by means of a connecting screw 49, or other ordinary securing means, said contact 48 being connected in any desired ordinary and well known manner with a corresponding terminal of a connecting plug, incandescent lamp, or other device to be supplied 105 with electricity or embraced within the same electric circuit with said stationary terminals and switching mechanism.

The terminal or base 50 of the binding post 51 is of the usual form and adapted 110 to be electrically connected with the outer terminal or shell 52 of a lamp or other electric device in any desired ordinary and well known manner. And the binding post 51 is connected with the other lead-in wire 115 or line wire 44 by means of a connecting screw or binding screw 53. (See Figs. 1, 2 and 5.)

I claim:

1. In a device of the class described, the 120

combination of a contact terminal, a movable contact member, resilient actuating means in operative engagement with said movable contact member, a stationary 5 detent adapted to engage and releasably hold said resilient actuating means at a tension and means for rotating said actuating means circumferentially relative to its length to put same under tension alternately in different directions.

2. In an electric switch, the combination of a contact terminal, a movable contact member, resilient actuating means adapted to move said movable contact member into 15 and out of engagement with said first-mentioned contact terminal, and checking means adapted to engage and releasably hold said resilient actuating means at a tension in a plurality of predetermined positions successively independently of said movable contact member, and means for rotating said actuating means circumferentially relative to its length to put same under tension alternately in different directions.

25 3. In an electric switch, the combination of a contact terminal, a movable contact member, resilient actuating means adapted to move said movable contact member into and out of engagement with said first-mentioned contact terminal, to open and close an electric circuit, and stationary checking means adapted to engage and releasably hold said resilient actuating means in a plurality of predetermined directions independently of said movable contact member, and means for rotating said actuating means circumferentially relative to its length to put same under tension successively in different directions related to said predetermined positions.

40 4. In an electric switch, the combination of a contact terminal, a movable contact member, an actuating spring adapted to move said movable contact member into and out of engagement with said first-mentioned contact terminal, to open and close an electric circuit, a stationary detent adapted to engage and releasably hold said actuating spring at a tension independently of said movable contact member, and means for rotating said actuating means circumferentially relative to its length to put same under tension alternately in different directions.

45 5. In an electric switch, the combination of a contact terminal, a movable contact member, resilient actuating means in operative engagement with said movable contact member, a stationary detent adapted to engage and releasably hold said resilient actuating means at a tension, and means for rotating the resilient actuating means circumferentially relative to its length to put same under tension alternately in different directions.

6. In an electric switch, the combination of a contact terminal, a movable contact member, resilient actuating means in rotative engagement with and adapted to move said movable contact member into and out of contact with said first-mentioned contact terminal, to open and close an electric circuit, and means for rotating said resilient actuating means circumferentially relative to its length to put same under tension alternately in different directions to bias said movable contact member in predetermined selectable positions.

7. In an electric switch, the combination of a stationary contact terminal, a movable contact member, resilient actuating means adapted to move said movable contact member into and out of contact with said stationary contact terminal, to open and close an electric circuit, and means for rotating said actuating means circumferentially relative to its length to put same under tension successively in different directions.

8. In an electric switch, the combination of a stationary contact, a movable contact member, an actuating spring adapted to move said movable contact member into and out of contact with said stationary contact, to open and close an electric circuit, stationary checking means adapted to engage and releasably hold said actuating spring at a tension in different positions of its path of movement successively, and means for rotating said actuating spring circumferentially relative to its length to put same under tension successively in different directions.

9. In an electric switch, the combination of a pair of contact terminals, a movable bridging switch member, an actuating spring rotatively mounted in operative engagement with said movable bridging member and adapted to move the same into and out of engagement with said contact terminals, to open and close an electric circuit, guiding means in guiding engagement with said bridging member, stationary spring-engaging checking means adapted to engage and releasably hold said actuating spring in different positions in its path of movement successively, and means for turning said actuating spring upon its axis to set the same at a tension in releasable engagement with said spring-engaging checking means.

10. In an electric switch, the combination of a contact terminal, a movable contact member, a stationary guide in guiding engagement with said movable contact member, reciprocatory actuating means in operative engagement with and adapted to actuate said movable contact member in opposite directions with respect to said contact terminal alternately, and detents adapted to releasably engage and resist the movement of said reciprocatory actuating means in the direction of said contact terminal.

11. In an electric switch, the combination of a contact terminal, a movable contact member, reciprocatory actuating means in operative engagement with and adapted to actuate said movable contact member alternately in opposite directions with respect to said first-mentioned contact terminal, and a slotted guide provided with detents adapted to releasably engage and successively resist and permit the free movement of said reciprocatory actuating means with respect to said first-mentioned contact terminal.

12. In an electric switch, the combination of a pair of contact terminals, a movable contact member, reciprocatory actuating means in operative engagement with and adapted to actuate said movable contact member alternately in opposite directions with respect to said contact terminals, to open and close an electric circuit within which said terminals are adapted to be embraced, and a guide in guiding engagement with said movable contact member and provided with a slot or opening for receiving said reciprocatory actuating means, said guide having detent shoulders adapted to releasably engage and alternately restrain and permit the free movement of said reciprocatory actuating means.

13. In an electric switch, the combination of a pair of contact terminals, a movable contact member, actuating means comprising a resilient element adapted to move said movable contact member alternately in opposite directions with respect to said contact terminals, to open and close an electric cir-

cuit in which said terminals are adapted to be embraced, a guide in guiding engagement with said movable contact member, detent shoulders provided with an opening therebetween and adapted to alternately check and permit the free movement of said reciprocatory actuating means and movable contact member, and means for positioning and releasably holding said resilient element at a tension in different predetermined positions in predetermined order.

14. In an electric switch, the combination of a pair of contact terminals, a movable contact member, actuating means comprising an actuating spring rotatively mounted and having a reciprocating spring arm in operative engagement with said movable contact member and normally projecting outward laterally from and at an oblique angle with respect to the axis of rotation of said spring and adapted to actuate said movable contact member transversely in opposite directions with respect to said axis of rotation of said spring, a slotted guide in guiding engagement with said movable contact member and provided with detent shoulders adapted to alternately check and permit the free movement of said reciprocatory actuating means and movable contact member, and means for rotatively supporting and intermittently rotating said actuating spring.

Signed at Chicago in the county of Cook and State of Illinois, this 2nd day of July, 1923.

WILLIAM LINDSAY.
